UNITED STATES PATENT OFFICE.

SIDNEY M. DUMONT, FRANK DUPRAZ, AND J. DICKASON, OF VEVAY, INDIANA.

IMPROVED STEERING APPARATUS.

Specification forming part of Letters Patent No. 55,257, dated June 5, 1866.

To all whom it may concern:

Be it known that we, SIDNEY M. DUMONT, FRANK DUPRAZ, and JOHN DICKASON, all of Vevay, Switzerland county, State of Indiana, have invented certain new and useful Improvements in Steering Apparatus for Vessels; and we do hereby declare the following to be a full, clear, and exact description thereof, reference being had to the accompanying drawings, making part of this specification.

Our invention consists of certain attachments between the pilot-wheel and rudder of a vessel, whereby the rudder, from its midway position to either side, may be operated by a progressive power or mechanical leverage, and the circuit-connection of rope always remain taut.

In the accompanying drawings, A² is an ordinary pilot-wheel. In place of the common cylindrical hub of the wheel, we construct the hub of double cones A A', grooved spirally on their faces, as shown. The tiller-rope B B' is rigidly secured to the hub at a, the part B being designed to operate upon cone A and sheave-pulley C, and from thence pass down to idler D, and connect, in the ordinary way, as shown, through tiller E to the rudder F. The portion B' of the tiller-rope operates upon cone A', and over sheave-pulley C' and idler D', connecting in a similar manner to the rudder.

To compensate for and take up the loss or

gain of rope in running over the differing diameters of the cones A A', and also the unequal tension incident to the varying positions of the tiller E, the sheave-pulleys C C' are grooved laterally and spirally, as shown, the spiral grooves agreeing with those on the cones A A'. The largest diameters *w* of the sheave-pulleys oppose the smallest diameters *x* of the cones A A', the smallest diameters *y* opposing enlarged diameters of the cones. The enlargement *z* compensates for the slack incident to the motion of the tiller E.

By this device the tiller-rope B B' is taut in every position of the pilot-wheel and rudder, and by means of the cones A A' the leverage is greatest where most power is necessary, when the rudder is "hard up" on either side, the tiller-rope B or B' being then on the small diameter of the cone A or A'.

We claim—

In the described combination with the double cone-shaped pilot-wheel hub A A', the compensating sheave-pulleys C C', as described, and for the purpose specified.

In testimony of which invention we hereunto set our hands.

SIDNEY M. DUMONT.
FRANK DUPRAZ.
JOHN DICKASON.
